G. W. McCACKEN, OF MOUNDSVILLE, WEST VIRGINIA.

VALVE-CAGE-LIFTING TOOL.

1,314,264.

Specification of Letters Patent. Patented Aug. 26, 1919.

Application filed February 7, 1919. Serial No. 275,578.

To all whom it may concern:

Be it known that I, ELI M. HEMPHILL, a citizen of the United States of America, and resident of Moundsville, county of Marshall, 5 and State of West Virginia, have invented certain new and useful Improvements in Valve-Cage-Lifting Tools, of which the following is a specification.

This invention relates to a lifter for the 10 valve cages of internal combustion engines.

The primary object of the invention is to provide a simple, inexpensive and efficient tool whereby the valve cages of motors of the valve-in-head type may be readily withdrawn.

A further object is to provide a tool of the character mentioned having a lifting yoke which is readily shiftable to render the bar or handle a lever of either the first 20 or the second class.

A still further object is to provide a device which is designed not only as a lifter for valve cages, but also as a tool by means of which the usual rocker-arm may be raised 25 out of engagement with the cam-rod, thereby to free the valve and valve-cage.

With these and other objects in view, the invention resides in the features of construction which will hereinafter be fully described, reference being had to the accompanying drawings, in which—

Figure 1 is a side elevation of the invention;

Fig. 2 is an enlarged cross section on line 35 2—2, Fig. 1, illustrating the lifting yoke in cage-lifting position;

Fig. 3 is an enlarged cross section on line 3—3, Fig. 1, showing the rocker-arm lifting member;

Fig. 4 is a vertical section of an engine cylinder of the valve-in-head type, illustrating the application of the invention as a cage lifter, with the bar employed as a lever of the first class;

Fig. 5 is a side elevation of the invention applied as a valve lifter, with the bar employed as a lever of the second class; and

Fig. 6 is a similar view illustrating the application of the device as a lifter for the 50 rocker arm of the cylinder.

Referring to said drawings, in which like designating characters distinguish like parts throughout the several views—

1 indicates the cylinder of an internal combustion engine of a common valve-in-

head type, and 2 designates a common form of cage seated in the head of the cylinder and normally secured in place by a ring or sleeve-nut 3 threaded into the cylinder thereagainst. A valve 4 has its stem 5 extended vertically through the cage and projecting above the latter. A spiral spring 6 is interposed between the upper face of the cage 2 and a pin or key 7 which is projected transversely through the outer end of the 65 valve stem, or between the cage and a cupped washer 8 which is held in place by such pin or key.

To effect removal of the valve 4 or to gain access to the interior of the cylinder 1, the 70 valve cage 2 must be withdrawn. To preliminarily free said cage for withdrawal the usual rocker-arm 9 pivoted upon a support, as 10, must be shifted or swung from its operative position in which one end seats 75 upon the end of the valve stem 5 and the other end upon a cam-rod 11; and then the sleeve-nut 3 must be turned out of threaded engagement with the cylinder.

Due to accumulation of carbon and like 80 foreign matter between the walls of the cage and the cylinder, the cage frequently becomes "stuck," or so firmly cemented in its seat that it effectually resists withdrawal except under the application of extraordinary force. Various forms of tools heretofore employed to accomplish the withdrawal of such sticking or difficultly removable cages either are inadequate for the purpose or are 85 objectionable in that they tend to bend or otherwise injure the valve stem. The objectionable features of tools of this class are overcome by the device shown in the drawings, in which the numeral 12 indicates a bar or lever which is preferably of rectangular form in cross section and which carries at one end thereof a yoke 13 designed to engage the valve-spring 6. Said yoke is made of a single piece of material and comprises a pair of similar oppositely disposed 90 arms 13^a which are terminated at their lower ends by inturned beveled hooks 13^b which are designed for introduction between the coils of the valve spring and which are separated a distance at least equal to the 95 diameter of the valve stem so that the latter may be received therebetween, as shown in Figs. 2 and 5. Said arms are united by a cylindrical stem 13^c which rests upon the 100 top surface of the lever 12 and upon which 105

1 indicates the cylinder of an internal combustion engine of a common valve-in-

the yoke has free swinging movement with respect to said lever.

The yoke 13 is shiftably disposed in a longitudinally extending channel or slideway 14 provided between upright lugs 15 and 16 formed on the upper face of the lever and is retained in said slideway by suitable overlying means, as by a plate 17 having its opposite ends attached to said lugs. The foremost lug 15 is located closely adjacent to the front end of the lever and is adapted to receive the stem 13^c of the yoke thereagainst when the tool is used for withdrawing valve cages, with the lever employed as a lever of the first class, as shown in Fig. 4. The lug 16 is spaced from the lug 15 the distance necessary to permit the yoke to occupy proper position when the lever is employed as a lever of the second class, as shown in Fig. 5, this use being frequently desirable in close places or when the position of the engine cylinder is such that free operation of the lever as a lever of the first class is interfered with, as when the cylinder is located close to the dash of an automobile.

In practice, when the cylinder is readily accessible, the yoke 13 is moved into seating relation to the lug 15 and, with the underside of the lever disposed, as shown in Fig. 4, in seating relation to the closely adjacent rocker arm 9 or to the support 10, as may be most convenient. The yoke is then swung into a position wherein the hooks 13^b enter between two adjacent coils of the spring 6. Relatively small power applied downwardly to the outer end of said lever will result in such a force being applied to the spring and, through the latter and the intermediate parts to the valve cage 2, as will readily overcome the most obstinate resistance offered to the withdrawal of such cage. As is obvious, due to the fact that the yoke is free to swing on its support, a straight vertical pull is at all times exerted in which there is no tendency to bend or otherwise distort the valve stem.

When free movement of the tool would otherwise be interfered with, the yoke is moved back along the slideway 14 toward or against the lug 16, and, with the front end of the lever fulcrumed upon the rocker-arm 9 or upon the support 10, as shown in Fig. 5, the yoke is swung into the position wherein its hooks engage the spring; whereupon elevation of the outer end of the lever will accomplish the unseating of the valve cage.

Preliminary to effecting the withdrawal of the cage in the manner hereinbefore described the rocker arm 9 must of course be freed from engagement with the valve stem 5. To provide for such disengagement of the rocker arm by means of the same tool by which the valve cage is thereafter withdrawn, I rigidly mount upon the lever 12 at a suitably spaced distance from the outer

end of the latter the upright member 18^a of an L-shaped arm 18. When it is desired to disengage the rocker arm, the horizontal member 18^b of said arm 18 is placed in underlying relation to said rocker arm at a point between the outer end of the latter and its support 10 and the said outer end of the lever is fulcrumed either upon said rocker arm or said support. A slight elevating force then applied to the free end of the tool will suffice to disengage from the cam rod 11 the outer end of the rocker arm, which may then be slightly shifted in a lateral direction to remove said end from overlying relation to said cam rod, whereupon said rocker arm is permitted to gravitate to an inclined position wherein its inner end is withdrawn from overlying relation to the valve cage.

What is claimed is—

1. A valve-cage lifting tool comprising a lever provided adjacent to one end with a longitudinal slideway, and a lifting yoke carried in said slideway, said yoke consisting of a horizontal stem and a pair of divergent downwardly extending arms, said arms being provided with inwardly directed hook terminals, said stem being slidably disposed in said slideway and having pivotal relation to said lever whereby said yoke occupies vertical position irrespective of the position assumed by said lever. 90

2. A valve-cage lifting tool comprising a lever provided adjacent to one end with a longitudinal slideway, and a lifting yoke carried in said slideway, said yoke consisting of a horizontal stem and a pair of divergent downwardly extending arms, said arms being provided with inwardly directed hook terminals, said stem being slidable in said slideway to render said lever, according to its position on the latter, a lever of either the first or second class. 100

3. A valve-cage lifting tool comprising a lever provided adjacent to one end with a longitudinal slideway, and a lifting yoke carried in said slideway, said yoke consisting of a horizontal stem and a pair of divergent downwardly extending arms, said arms being provided with inwardly directed hook terminals, said stem being slidable in said slideway to render said lever, according to its position on the latter, a lever of either the first or second class, said yoke being free to swing on said lever so that it occupies vertical position irrespective of the inclination of said lever. 110

4. A valve-cage lifting tool comprising a lever having on its upper face adjacent to one end thereof two upright lugs, one located rearward of and at a spaced distance from the other to provide an intermediate slideway, a member overlying said slideway and attached to said lugs, and a valve-spring engaging yoke movable in said slideway, said 125 130 135

yoke comprising an intermediate member and a pair of integral divergent arms, said intermediate member being seated on said lever in said slideway and having free pivotal movement on its seat, and said arms being terminated by inwardly directed hooks.

5. A valve-cage lifting tool comprising a lever having on its upper face adjacent to one end thereof two upright lugs, one located rearward of and at a spaced distance from the other to provide an intermediate slideway, a member overlying said slideway and attached to said lugs, and a valve-spring engaging yoke movable in said slideway,

10

15

disposed divergent downwardly inclined arms with inturned hook terminals, said intermediate member being seated on said lever in said slideway and having free pivotal movement on its seat, said lever being adapted to serve as a lever of the first class when said yoke occupies an advanced position in said slideway and as a lever of the second class when said yoke occupies a re- 25 tracted position.

In testimony whereof, I affix my signature in presence of two subscribing witnesses.

ELI M. HEMPHILL.
